TRAVELING BAG

Edward E. Adams, Washington, D. C.

Application August 29, 1950, Serial No. 11,981

Term of patent 14 years

(Cl. D87—5)

To all whom it may concern:

Be it known that I, Edward E. Adams, a citizen of the United States of America, and a resident of Washington, D. C., have invented a new, original, and ornamental Design for a Traveling Bag, of which the following is a specification, reference being had to the accompanying drawings, forming a part thereof.

Figure 1 is a perspective view of a traveling bag, showing my new design, with the handles in raised position;

Figure 2 is an end elevational view looking from the left side of Figure 1, but with the short handles in lowered position and a portion of the shoulder strap broken away for convenience of illustration; and

Figure 3 is an end elevational view similar to Figure 2 taken from the right side of Figure 1.

I claim:

The ornamental design for a traveling bag, substantially as shown and described.

EDWARD E. ADAMS.
